Orkin & Hanson, P.C.(57) **CLAIM**

The ornamental design for a lacrosse glove, as shown and described.

DESCRIPTION

FIG. 1 is a front view of a lacrosse glove;

FIG. 2 is a rear view of a lacrosse glove;

FIG. 3 is a top plan view of a lacrosse glove;

FIG. 4 is a bottom plan view of a lacrosse glove;

FIG. 5 is a left side view of a lacrosse glove;

FIG. 6 is a right side view of a lacrosse glove; and,

FIG. 7 is a perspective view of a lacrosse glove.

The broken lines shown in the drawing on the glove are understood to represent stitching.

The fragmentary crosshatch pattern shown in the drawing is understood to represent fabric and is repeated uniformly throughout the areas shown.
